CLAIM

The ornamental design for an electronic device, as shown and described.

DESCRIPTION

This application is related to co-pending applications with Ser. Nos. 29/582,639 and 29/582,668, filed on Oct. 28, 2016, the disclosures of which are incorporated by reference herein.

FIG. 1 is a first perspective view of an electronic device, taken from above.

FIG. 2 is a front view of the electronic device of FIG. 1.

FIG. 3 is a back view of the electronic device of FIG. 1.

FIG. 4 is a top view of the electronic device of FIG. 1.

FIG. 5 is a bottom view of the electronic device of FIG. 1.

FIG. 6 is a right-side view of the electronic device of FIG. 1.

FIG. 7 is a left-side view of the electronic device of FIG. 1; and,

FIG. 8 is a second perspective view of the electronic device of FIG. 1.

The additional broken line subject matter seen in FIG. 8 depicts environmental subject matter only and forms no part of the claim.

The broken lines represent features of the electronic device that form no part of the claimed design.
